UNITED STATES PATENT OFFICE.

ERNEST EDWARD SUMNER, OF LONDON, ENGLAND, ASSIGNOR TO LANSTON MONOTYPE MACHINE COMPANY, OF PHILADELPHIA, PENNSYLVANIA, A CORPORATION OF VIRGINIA.

RECORD-STRIP COMPOSING OR PREPARING MACHINE.

1,283,958.

Specification of Letters Patent.

Patented Nov. 5, 1918.

Application filed December 29, 1916. Serial No. 139,628.

To all whom it may concern:

Be it known that I, ERNEST EDWARD SUMNER, a subject of the King of Great Britain, residing at #13 Ambleside road, Willesden, London, N. W., England, have invented certain new and useful Improvements in Record-Strip Composing or Preparing Machines; and I do hereby declare the following to be a full, clear, and exact description of the same, reference being had to the accompanying drawings, forming part of this specification, and to the characters of reference marked thereon.

This invention relates to machines for composing or preparing patterns, record-strips or controllers, such as are employed to control the action of automatic type-casting and composing machines, each unit, character, symbol, or justification fraction being set up or represented in the record-strip by one or more signal components or perforations through the instrumentality of key controlled punches or signal producing devices.

It has been usual, hitherto, to compose the line of matter so that when being cast the fractions necessary to justify the line have been added to certain predetermined "spaces" or space type-bodies which are variable in setwise measurement for justification purposes, as, for example, with the invention according to the U. S. Patent to J. Sellers Bancroft and Mauritz C. Indahl, No. 944,405, dated December 28th, 1909, but it has also been proposed, for example, according to the invention of the U. S. Patent to the above inventors No. 1,094,630, dated April 28th, 1914, to add the justification fraction for a line to the "type" bodies, that is to say, to bodies of predetermined and fixed point sizes such as characters, points, quads, etc., as distinguished from "space" type bodies. It is the chief object of the present invention to provide improved and simplified controllable mechanism whereby the justification fraction for a given line of composition can be applied to any number of the individual "type" bodies in the composed line.

The signals for type are in general composed of two components, one denoting or indicating position, the other position and dimension, since in addition to determining in the casting machine the position of the die or matrix, it also controls the dimen-

sioning of the mold for the designated matrix, and the signal member or punch for producing this component is coupled with the line-measuring mechanism to effect the recording on the line measure of the unit value of each type; these components will be referred to hereinafter as positioning and dimensioning components respectively.

The dimensioning component of a space signal controls in the casting machine the setting or positioning of the normal mold-dimensioning mechanism as in the case of a type while the other component of the space signal controls the adjustment of a transfer mechanism which effects a change in the value of the normal mold-dimensioning mechanism when combined with a supplementary or justification mold-dimensioning mechanism as is the case when spaces are being cast, and the punch in the composing machine which produces the transfer component is coupled with mechanism whereby the line-measuring mechanism registers the unit value of the unjustified space at a fixed amount.

The signals for the justification fraction for the composed line are formed at the end of the line and each comprises two components. As, however, in the organized casting machine the record-strip is passed therethrough in the order reverse to composition, the justification signals are presented at the record-strip interpreting mechanism of the casting machine before the signals denoting type and spaces. These justification signals function in the casting machine to effect the adjustment or setting of the supplementary mold-dimensioning mechanism which is only rendered operative to dimension the mold in conjunction with and in addition to the normal mold-dimensioning devices when spaces are being cast. The supplementary mold-dimensioning devices are rendered operative by the transfer component of the space signal which, as already stated, acts upon the transfer mechanism, while the setting of the normal mold-dimensioning devices is effected through the dimensioning component of the signal be it space or type.

With the above mechanism the dimension indicated for any given position of the normal mold-dimensioning devices is two units less when controlled by the dimen-

sioning component of a space signal than when controlled by the like component of a type signal, and as the same punch can be used for producing the dimensioning components of both kinds of signals, type and space, provision is made in the composing machine whereby the register on the line-measuring mechanism will be two units less when recording a space than when used for 10 a type.

In accordance with the present invention improved mechanism is provided for coupling at will the transfer component of the space signal with the type signals and for 15 cutting out the unit registering or measuring mechanism of the space signal, so that the unit value of the type signal will be registered; thus the signal, when being interpreted in the casting machine, will effect 20 the setting of the normal mold-dimensioning devices and will also effect the coöperation therewith for dimensioning the mold for the designated type of the supplementary or justification mold-dimensioning 25 devices.

The addition of this transfer component to the type signal so that in the casting machine the mold is dimensioned by the conjoint action of the normal and supplementary or justification mold-dimensioning 30 device diminishes the value of the designated type by two units, the deficiency which is made up and applied through the medium of the justification signal which is increased 35 in value to the extent of two units of the set for each of the type signals to which the transfer component has been applied.

In carrying out the present invention there is provided a hand-operated or hand-controlled mechanism by which the punch 40 for the transfer component of the space signal can be coupled with a part of the machine which is moved or is operated with every type signal so that this punch is no longer operated by its motor but by the said 45 part, and a detachable coupling between the actuating member for this punch and the units-measuring mechanism is operated by which the units-measuring mechanism can 50 be disconnected so that it takes no part in the measuring of the value of the type signal to which the transfer component is coupled.

In the machine to which the invention is 55 particularly applicable there is a universal bar which is operated by all the type punches and under the influence of a motor serves to return the punches after each operation, and in accordance with the present 60 invention a pivoted lever, one end of which is coupled with the transfer punch-bar, carries at its other end a link which can be swung into and out of operative engagement with an arm of the aforesaid universal bar, 65 and the movement which effects this cou-

pling or uncoupling also effects the coupling and uncoupling of the units-measuring mechanism with the transfer punch.

Referring to the accompanying drawings.

Figure 1 is a sectional elevation of part 70 of a typographical composing machine embodying the present invention.

Fig. 2 is a perspective view of the mechanism of the invention separately.

Fig. 3 is a rear elevation of part of the 75 mechanism shown in Fig. 1.

Figs. 4 and 5 are section elevations showing the movable coupling between the transfer punch and the units measuring mechanism, and

Fig. 6 is an end elevation of Fig. 4.

The composing machine to which the invention is herein shown applied and in connection with which it will be herein described is that of Patent #944,405, previously referred to, to the specification of which attention is directed for a full and complete description of the machine, it being sufficient for present purposes to designate in general only those parts thereof 90 with which the mechanism of the present invention is more intimately related, for example, (employing the same reference numerals as those of the patent) the keys 180 pneumatically operating the punch bar 95 motor pistons 29, connected with the punch bar levers 17 and punch bars 15, (the punch bar shown in Fig. 1 being that of the transfer or space punch); the line measuring mechanism including the stop bars 13 on 100 the outer ends of levers each operated from a dimensioning punch bar 15 through a lever 20 and a vertically movable bar 40, the units rack 11 slidable in the units rack carrier 42 operated from the universal bar 105 19, the latter being connected by arms with the shaft 34 and by the arm 35 and link 36 with the return motor piston 37, the units wheel 7 and the line scale rack 14; the justification indicating mechanism identified by 110 the indicator drum 8 and the space counter or pointer 14*, the latter being carried by the vertical ratchet bar 85 driven upwardly by pawl and ratchet means including the operating arm 91 and allowed to fall when 115 desired by a suitably operated trip.

In accordance with the present invention there is pivotally supported in a bracket 7¹ (Fig. 2) secured to the machine frame, a lever 8¹ one end of which by a pin and slot 120 connection is coupled with the transfer punch bar 15. To the other end of the lever 8¹ is pivotally connected, at a point intermediate its ends, a bar or rod 9.

At its lower end the rod 9 is formed with 125 a hook or slot 10, which when the rod is turned on its pivot 12 engages a pin 16 on the arm 35 of the universal bar 19 as shown in full lines in Fig. 1. In this position, when a key is operated to actuate the 130

punches for a type signal, the universal bar 19 in rising, through its engagement with the shoulders on the punch-bars, acts to pull down the rod 9, lowering the rear end of the lever 8¹ and raising its forward end to elevate and actuate the transfer punch bar 15 and its punch 1 independently of its motor. As the universal bar is actuated with each type signal, the transfer component will be 10 added to all type signals so long as the rod 9 is coupled with the universal bar 19.

When the bar 9 is rocked or turned on its pivot 12 into the position indicated in broken or dotted lines in Fig. 1 and is thus uncoupled from the rod 16, then the transfer punch 1 will respond only to its motor and be uninfluenced by the bar 19 as above described, and will then only operate as a component of a space signal.

20 As already stated, the transfer component punch 1 is coupled with the units stop pertaining to the space signal to effect the recording of the units value of the space signal, but when the transfer component of the 25 space signal is added to the type signal as proposed by this invention, the unit value to be recorded is no longer the constant value of a space signal but the variable value of a type signal, and, therefore, the units 30 measuring mechanism of the space signal must be rendered inoperative so that the units will be measured from the type signal, the unit stop for which is coupled with the dimensioning component or punch of the 35 type signal.

The lever 20 connecting the punch bar 15 of the transfer component of the space signal punch 1 is coupled with the corresponding unit-stop-actuating bar 40, and for effecting the coupling and uncoupling of this stop, in accordance with this invention, the bearing 18 in the punch bar 15 for the lever 20 may be opened and closed to form a detachable coupling. This bearing is formed 45 in two parts which together embrace a rounded portion 21 on one end of the lever 20. The part 22 of the bearing is formed on or in one with the punch-bar, but the lower part 23 is formed of a piece mounted 50 to slide between guides formed on the bar, and is arranged to pass through an opening in the punch-bar (see Figs. 1, 4, 5 and 6).

When the movable part 23 of the bearing is in its forward position (see Fig. 4) the lever 20 is moved by the punch-bar and the units value of a space signal is recorded. This is the condition of operation when the mechanism of the present invention is inoperative.

60 When, however, the mechanism of the invention is in operation and the transfer signal producing member is operated from the universal bar 19, the movable part 23 of the bearing is withdrawn to the position indicated in broken lines, Fig. 1, and in full

lines in Fig. 5, so that when the punch-bar is raised by the lever it rises without carrying with it the units stop operating lever 20 of the transfer component punch 1.

To facilitate the adjustment of the movable part of the bearing and to effect its adjustment simultaneously with the adjustment of the punch-bar operating levers, there is coupled to the sliding part 23 a lever 24 which is pivoted to the lever 8¹ at 25 70 and is coupled at its upper end by a link 26 to the bar 9. The coupling shown is in the form of a pin projecting laterally from the part 23 and normally seating between upturned wedge shaped prongs formed by providing the lower end of lever 24 with a fork and bending the prongs of the fork upwardly.

80 A spring detent 27 is provided and is adapted to engage with one or other of two notches 28, 29¹, on the sliding part to hold it in either of its adjusted positions.

The rod 9 is operated conveniently by a sliding bar 30 mounted upon studs 31, which are secured conveniently to the outside of 90 the machine frame and pass through slots 32 in the bar. At its inner end the bar 30 has a downwardly extending slotted portion 33 which embraces a stud 36¹ on the upper end of the rod, and the slot 38 is sufficiently deep 95 to accommodate and retain the stud in both of its positions of adjustment, and when the rod 9 is reciprocated by the bar 16.

95 A spring detent 39 is secured to the machine frame and arranged to engage one or 100 other of two notches 41, 42¹, in the bar to retain it against accidental movement when in either of its adjusted positions.

In the class of machine to which the present invention refers there is a justification indicator 8 cooperating with the line-measuring mechanism from which the operator or compositor ascertains what keys it is necessary to operate to form in the record-strip the justification signals for the line, 105 and co-acting with this indicator is a space counter 14^x which is operated with each signal for a justification space. In the organized machine this space counter is operated by a motor, the air or operative fluid for 110 which is supplied from the motor of the transfer component punch of the space signal. Since in accordance with the present invention, when the mechanism is in operation the transfer punch is operated independently of its motor, and, therefore, the motor for the space counter will not be energized, it is necessary for the purposes of this invention that the space counter be operated 115 with each type signal with which the transfer component punch is coupled, otherwise the fraction presented by the justification indicator would be inaccurate.

120 A convenient method of operating the space counter for the purposes of the pres- 130

ent invention comprises a lever 43 which is pivoted intermediate its ends to the machine frame at 44. One end of this lever is connected by a link 45 to the operating arm 91 for the space counter which is normally operated by the space counter motor. The other end of the lever 43 is connected by a link 46 with the rod 9 which is capable of being coupled with so as to be operated by the universal bar.

Each time the rod is raised by the universal bar the lever will be actuated to lift the space counter one division.

Claims:

15. 1. In a record strip composing or preparing machine provided with type signal producing devices, a member movable by any one of said devices, space signal producing devices including a transfer signal producing member, line measuring mechanism and space counting mechanism, and in combination therewith, mechanism for connecting said movable member with said transfer signal producing member and with the space counting mechanism whereby the said transfer signal producing member and the said space counting mechanism may be operated whenever a type signal producing device is operated, and means for disconnecting said transfer signal producing member from the line measuring mechanism.
20. 2. In a record strip composing or preparing machine provided with line measuring mechanism, a series of signal producing devices including dimensioning signal producing members and a transfer signal producing member and a member movable by any one of said dimensioning signal producing members, and in combination therewith, a detachable coupling mechanism for connecting the transfer signal producing member with said movable member and for simultaneously disconnecting the transfer signal producing member from the measuring mechanism.
25. 3. In a record strip composing or preparing machine provided with a series of signal producing devices including dimensioning signal producing members and a transfer signal producing member, and a universal bar movable by any one of said dimensioning signal producing members, and in combination therewith, a lever connected with said transfer signal producing member and means for detachably connecting said lever with the universal bar.
30. 4. In a record strip composing or preparing machine provided with a series of signal producing devices including dimensioning signal producing members and a transfer signal producing member, and a universal bar movable by any one of said dimensioning

signal producing members, and in combination therewith, a lever connected with said transfer signal producing member, a second lever connected with said first named lever and mechanism for detachably coupling the second named lever with the universal bar.

5. In a record strip composing or preparing machine, a space or transfer signal producing member and line measuring mechanism including a lever connected at one end with said member, in combination with mechanism for temporarily disconnecting said lever and said member.

6. In a record strip composing or preparing machine provided with type and space signal producing punches, space counting mechanism normally operated simultaneously with the operation of a space signal producing punch, and in combination therewith, mechanism connecting said counting mechanism with a type signal producing punch, whereby the counting mechanism is capable of being operated simultaneously with the operation of said type signal producing punch.

7. An attachment for a record-strip composing machine provided with a series of key controlled signal producing devices including a space punch, a space counting mechanism and a universal bar movable by any one of said signal producing devices, said attachment comprising a lever mechanism adapted to connect said space punch and said universal bar and a lever adapted to connect at one end with said lever mechanism and at the other end with said space counting mechanism.

8. In a record strip composing or preparing machine provided with a series of type signal producing devices, a universal bar movable by any one of said devices, a space signal producing device including a space punch bar, line measuring mechanism, including a stop operating lever, normally connected at one end with said space punch bar and space counting mechanism, and in combination therewith, a lever connected at one end with said space punch bar, a second lever connected with said first named lever at the opposite end of the latter, mechanism for detachably connecting said second named lever with the universal bar, means connected with said second named lever for disconnecting said stop operating lever from said space punch bar and lever mechanism connected with said second named lever and said space counting mechanism.
